UNITED STATES PATENT OFFICE.

FRANK L. ENGLEHARDT, OF CHICAGO, ILLINOIS, ASSIGNOR TO W. H. MINER COMPANY, OF CHICAGO, ILLINOIS, A CORPORATION OF ILLINOIS.

DRAFT-RIGGING FOR RAILWAY-CARS.

No. 838,530.

Specification of Letters Patent.

Patented Dec. 18, 1906.

Application filed November 3, 1905. Serial No. 285,755.

To all whom it may concern:

Be it known that I, FRANK L. ENGLEHARDT, a citizen of the United States, residing in Chicago, in the county of Cook and 5 State of Illinois, have invented a new and useful Improvement in Draft-Rigging for Railway-Cars, of which the following is a specification.

My invention relates to improvements in 10 draft-rigging for railway-cars.

In the draft-rigging heretofore in use difficulty is sometimes experienced from the draw-bar strap or yoke buckling or bending under severe buffing strains.

15 The object of my invention is to provide a railway draft-rigging of a simple, efficient, and durable construction in which the draw-bar strap or yoke will be effectually protected against liability to buckle or bend under 20 buffing strains or blows.

My invention consists in the means I employ to practically accomplish this object or result—that is to say, it consists in connection with the draw-bar, draw-bar strap or 25 yoke, tandem-arranged springs and followers, and side plates or stop-castings, of a stationary guide-block secured to and extending between the side plates or stop-castings, and provided with guide-grooves having over- 30 hanging guide-flanges and guide-blocks secured to the upper and lower members of the draw-bar strap and having guide-flanges fitting in the guide-grooves on the stationary guide-block which is secured to the side 35 plates or stop-castings.

My invention also consists in the novel construction of parts and devices and in the novel combinations of parts and devices herein shown and described.

40 In the accompanying drawings, forming a part of this specification, Figure 1 is a side elevation, partly in longitudinal vertical section, of a draft-rigging embodying my invention. Fig. 2 is a plan view partly in horizontal section. Figs. 3 and 4 are vertical cross-sections on lines 3 3 and 4 4 of Fig. 2, respectively. Fig. 5 is a detail perspective view of the stationary guide-block which fits between and is secured to the side plates or 45 stop-castings, and Fig. 6 is a perspective view of one of the longitudinally-movable guide-blocks which is secured to and moves with the draw-bar strap or yoke.

In the drawings, A represents the center sills, A' the draft-timbers, A² the cross-sill, 55 A³ the buffer-block, and A⁴ the carry-iron, of a car. B is the coupler, B' the draw-bar, and B² the draw-bar strap or yoke, secured to the draw-bar by the customary bolts or rivets b. C C' are tandem-arranged springs, D 60 D the side plates or stop-castings, and E the followers, the stop-castings having stops d, d', d², and d³ for the followers to abut against, and also stops or shoulders d⁴, d⁵, d⁶, and d⁷ to limit the movement of the followers and the 65 compression of the springs. All these parts are or may be of any suitable or well-known construction familiar to those skilled in the art.

F is a stationary guide-block fitting and 70 extending between the side plates or stop-castings D between the two intermediate followers and rigidly and firmly secured to the side plates or stop-castings by a bolt f, which preferably also extends through the draft-timbers. The stationary guide-block F is further anchored to the side plates or stop-castings by tongues or projections f', which fit in vertical grooves d⁸ in the side castings D at the middle portion thereof. The stationary guide-block F is provided with upper 75 and lower channels f¹ and guide-grooves f², each having an inwardly-projecting flange f³ to embrace the corresponding co-operating flanges g of the movable or reciprocating 80 guide-blocks G, which are secured to and reciprocate with the draw-bar strap B². The guide-blocks G are secured one to the upper member of the strap B² and the other to the lower member of said strap B² on the inside 85 of the strap by rivets g'. As the draw-bar reciprocates the guide-blocks G, with their tongues or flanges g snugly fitting in the guide-grooves f², effectually prevent all liability or danger of the draw-bar strap buckling 90 or bending. By thus providing the side plates or stop-castings of the draft-rigging with guides or flanges which embrace and confine the upper and lower members of the draw-bar strap or guide devices rigidly secured thereto I am enabled to effectually prevent all danger of the draw-bar strap 95 buckling or bending, while at the same time permitting it to properly reciprocate in respect to the side plates or stop-castings, and 100 at the same time I do not materially increase 105

the cost of the draft-rigging or its dimensions.

I claim—

1. In a draft-rigging, the combination 5 with the draw-bar strap or yoke, tandem-arranged springs and followers, of stop-castings, guide-blocks secured to the upper and lower members of the draw-bar strap or yoke and a stationary guide-block rigidly secured 10 to and extending between the side plates or stop-castings and having guide-flanges embracing the guide-blocks on said strap or yoke and supporting and guiding said strap or yoke, and a bolt extending through said 15 guide-block and stop-castings, substantially as specified.
2. In a draft-rigging, the combination with the draw-bar strap or yoke having 20 guide devices secured thereto, of a stationary guide-block having guide devices embracing the guide devices on the draw-bar strap to prevent the strap from bending or buckling under buffing strains or blows, and stop-castings between which said guide-block extends and to which it is rigidly secured, and a bolt extending through said guide-block and stop-castings, substantially as specified.
3. In a draft-rigging, the combination 25 with the draw-bar strap or yoke having 30 guide-blocks secured thereto furnished with guide-flanges, of a stationary guide-block having guide-grooves in which the guide-flanges of the guide-blocks on the draw-bar strap fit and reciprocate, and stop-castings 35 between which said guide-block extends and to which it is rigidly secured, and a bolt ex-

tending through said guide-block and stop-castings, substantially as specified.

4. In a draft-rigging, the combination 40 with a stationary guide-block F, having guide-grooves f^2 , of a draw-bar strap having guide-blocks G furnished with guide-flanges g fitting and reciprocating in said guide-grooves of said stationary guide-block F, stop-castings between which said guide-block extends and to which it is rigidly secured, and a bolt extending through said 45 guide-block and stop-castings, substantially as specified.

5. In a draft-rigging, the combination 50 with the side plates or stop-castings having upright grooves d^8 , of a stationary guide-block F having tongues or projections f' fitting in said grooves d^8 , a bolt f extending through said block F and the side plates or 55 stop-castings, and a draw-bar strap provided with guide-blocks G having tongues or flanges g fitting in the guide-grooves f^2 of said stationary guide-block F, substantially as specified.

6. In a draft-rigging, the combination 60 with a stationary guide-block F having channels in its upper and lower faces, and horizontally-extending guide-grooves f^2 and inwardly-projecting flanges f^3 and a draw-bar strap having guide-blocks G furnished with guide tongues or flanges g , substantially as specified.

FRANK L. ENGLEHARDT.
